UNITED STATES PATENT OFFICE.

ALFRED J. WEBSTER, OF COLUMBUS, OHIO, ASSIGNOR TO JOSEPH A. JEFFREY, OF COLUMBUS, OHIO.

CONVEYER.

SPECIFICATION forming part of Letters Patent No. 735,921, dated August 11, 1903.

Application filed September 18, 1897. Serial No. 652,174. (No model.)

To all whom it may concern:

Be it known that I, ALFRED J. WEBSTER, a citizen of the United States, residing at Columbus, in the county of Franklin and State 5 of Ohio, have invented certain new and useful Improvements in Conveyers; and I do declare the following to be a full, clear, and exact description of the invention, such as will enable others skilled in the art to which it 10 appertains to make and use the same, reference being had to the accompanying drawings, and to the letters of reference marked thereon, which form a part of this specification.

Figure 1 is a side elevation of a sufficient 15 portion of a conveying apparatus to illustrate one manner of embodying my improvements. Fig. 2 is a top plan view, on an enlarged scale, of a portion of the conveyer. Fig. 3 is a side elevation illustrating the dumping mechanism. Fig. 4 is a side view of a diagrammatic 20 character, showing the different positions taken by one of the buckets during the operation of dumping. Fig. 5 is a plan view of a portion of the conveyer-chain. Fig. 6 is a 25 side elevation of the same. Figs. 7 and 8 are detailed views. Figs. 9 and 10 are respectively a plan and side elevation of a portion 30 of the loading-conveyer. Fig. 11 is a transverse sectional view of the conveyer. Fig. 35 12 is a detail of one of the bucket-links. Fig. 13 is a plan view of one of the connecting-pintles for the chain and the enlarged wearing-cylinder or bushing which is combined therewith, the adjacent parts of the chain being represented by dotted lines.

For the purpose of clearly illustrating one 40 of the uses to which may be put the several features of my invention I have shown in the drawings, somewhat conventionally and somewhat in detail, an endless conveyer adapted to receive coal from a point on the outside of a building and carry it to bins or receptacles in or adjacent to a boiler-room or from the pit or receptacle below the boiler room, where 45 they are received; but it will be understood that the several parts, more or less, of the invention can be used in mechanisms for other purposes and of modified construction.

In the apparatus shown use is made of two 50 parallel chains, each indicated as a whole by A. Each is shown as supported upon a series

of sprocket-wheels a a' a^2 a^3 a^4 a^5 , and the wheels for the two chains are arranged in pairs, those of each pair being connected to a shaft, as at a^6 , &c. Power is applied to the 55 chain from the shaft a^6 , it having also in the present machine a toothed gear a^8 , driven by the pinion a^9 , which is rotated by a gear-wheel a^{10} , in turn driven by a pinion a^{11} , actuated by a belt-wheel a^{12} , which is rotated 60 by the engine.

The chains illustrated are each of a peculiar form which I have devised. It is made up of sets of links, each set comprising a roller-link B, a bucket-link B', and two connecting-links B². The roller-link B is formed of two side bars b, connected at the ends by tubular or sleeve-like extensions b', integral with the side bars. These links B are forgings of great strength and have the side bars b separated or spaced in such a way as to receive a roller C between them, the roller being mounted upon a pin or journal c.

The bucket-links B' are solid bars or plates, each having the tubular end portions b² and 75 being provided with a transverse passage or aperture b³ and a laterally-projecting tubular boss E on its outer face or side in line with said aperture b³. The intermediate or connecting links of the set are formed of flat 80 strap-bars b⁵, which are secured by pintles to the roller-links B and the bucket-links B'. In the chains thus constructed are mounted the buckets D. These may be of any of the now well-known forms, though for most purposes I 85 prefer to have them of the character shown—that is to say, each formed with a relatively narrow flat bottom d, upwardly-diverging side walls d', and end walls d'', the latter extending upward, as at d'', above the side walls. 90 To the end of each bucket there is secured a sleeve or tube E², the latter having ears or lugs E', which are fastened to the bucket by rivets. F is a shaft or rod extending across the bucket and having its ends passed through 95 the said sleeves E², said sleeves and shaft being suitably connected together, and the ends of the latter are shaped to provide journals, which are mounted in bearings formed by the aforesaid apertures b³ in the bucket-links and 100 the aforesaid projecting bosses E on said links.

Each bucket is free to revolve in its supporting-bearings in the links B'. The lengths of the chain-links and the width of the bucket are so related that the latter shall be approximately close together edge to edge; but, unlike some bucket-carriers heretofore constructed, in the present case the chain-links are so arranged that on the draft side or "up-run" the buckets can be separated slightly, while on the slack side or downrun they will naturally tend to approach each other, as shown in Fig. 1. Hence at the point of loading, which is on the slack side, the edges of the buckets will be close together, so as to obviate the spilling of material delivered to them, and at the place of dumping they will be slightly separated, so as to insure sufficient clearness or free space to permit them to be tilted readily. This capability of the conveyer is facilitated by the form of chain employed and the manner of connecting the chains with the buckets. It will be observed that the bucket or load carrying links are pivoted to or connected with links which are intermediate the links that carry the supporting-rollers which run upon the ways or tracks Q. It follows that when the chain is slack, as on the lower run of the conveyer when the parts are arranged as shown in Fig. 1, the buckets and the portion of the chain to which they are directly connected may sag a little between each pair of supports formed by opposite bearing-rollers C, with the result that the edges of the buckets come close together, as stated.

G indicates a hopper adapted to receive and temporarily contain coal or other like material. From this hopper there leads a chute g. The lower end of this chute is so arranged as to deliver material continuously, if desired, to a series of buckets H. These are arranged in series and are each connected to and carried by a chain I. In this case each chain-link is composed of two longitudinally-extending bars i, which are securely riveted or otherwise secured to the upper portions of the sides of one of the buckets and extend or project beyond the side walls thereof. The projecting ends of the bars i are connected by a transverse shaft i', and on the end portions of said shafts beyond the buckets H are mounted rollers i'', adapted to engage with the teeth of the sprockets J. (See Figs. 1 and 9.) The driving-shaft J' is geared, preferably, by a chain J'' to one of the shafts of the main chain—as, for instance, to the shafts a¹³—and the diameter and speeds of the driving mechanism are such that the buckets H shall travel with the same speed as the buckets D when moving parallel to them. Each bucket H has a bottom h, preferably inclined, a front wall h', end walls h'', and an open top and an open side or discharge-mouth opposite the front wall. This open side of each bucket is closed when the bucket is loaded by a closing device h³, carried by the following bucket of the series.

When the buckets are moving longitudinally, the closing device h³ of each is held across the open side of the preceding bucket in the 70 series, and, preferably, there is a strip at h⁴ to insure tightness at the bottom; but as each bucket reaches the forward end of its horizontal movement and begins to pass upwardly around the sprocket J' at that point 75 the bucket is moved away from the closing device h³ and the contents of the bucket allowed to escape.

When the apparatus is in operation, the material that is delivered by the chute g passes 80 into the buckets H one after another, while they are moving along their "lower run," the open sides of the bucket being at this time upward. After each bucket H has been loaded and passes beyond the chute and begins to rise around the wheel J' the contents thereof are delivered, as above described, to the bucket D, which is traveling below. When the empty bucket H is descending around the other wheel J, its open 90 end is closed in the way described. In this way I can form suitably-sized charges or loads from the continuous stream of material delivered by the chute g and empty successively and without spilling them into the 95 buckets D. The latter after being filled travel onward around the wheels a² a³ a⁴ a⁵ to the place for the dumping at L.

The dumping is effected as follows: Upon the flooring or framework of the building or 100 the structure wherein the carrier is placed there are supported tripping devices, (indicated as a whole by M.) Each trip comprises two members, one indicated by m and the other by m', the first being adapted to 105 part a gradual but firm tilting of the bucket around its axis at the rod or shaft F, or at least cause it to commence such tilting, and the latter (the member at m') being adapted to continue the tilting movement and to hold 110 the bucket with firmness and steadiness in the dumping position.

The parts at m consist of an arm or bar n, rocking on an axis at n' and having at the end a trip arm n², which is preferably curved 115 or inclined somewhat in the direction of travel of the buckets and terminating in a hook-like extension n³. Preferably there is one of these arms n on each side of the carrier, and they are connected together rigidly by the 120 rock-shaft at n'. Each bucket is at or near its bottom provided with an outwardly-extending trip-arm o, which may be provided by fastening a rod to the under side of the bucket and allowing its extremities to project beyond it. These are so arranged as to 125 impinge upon the trip-arms n². The other member of the tripping mechanism at m' consists of a lug or projection n⁴, stationarily fastened to the framework, and with it there 130 can engage a lug o', secured to the bucket near its upper edge. Here also there is duplication of these parts n⁴ and o'—that is to say, there is one of each at each end of the

bucket. The operation of these dumping devices will be readily understood from the above description in connection with the drawings.

5 As the buckets approach the place for emptying the trip pin or rods o strike against the trip-arm n^2 or impinge upon it gradually, and immediately the bucket begins to tilt. As soon as draft is exerted by the buckets 10 upon the trip-arms n n^2 the latter begin to rise around their axis at n' , and the parts are so related that the tilting continues rapidly, but without shocks or jars; but there is manifestly a limit to the efficiency of the trip-arms n n^2 , as they cannot swing above a certain line without interfering with the following bucket. Just as soon as the bucket reaches the farthest position to which it can be carried by these parts at n n^2 the lug at o' 15 comes in contact with the lug at n^4 , and as this engagement occurs at a relatively low line the lugs can exert a quick and powerful leverage upon the bucket and throw it far enough over to instantly discharge its load 20 25 and at the same time throw it out of engagement with the arms at n n^2 . As the bucket moves along a little farther the lug at o' escapes from that at n^4 , and being now empty the bucket swings back into its normal position.

In some conveying mechanisms it is desirable to be able to deliver the material for a while at one place and then at another. In such case the member m of the tripping mechanism is arranged so that it can be adjusted into or out of working position. I have shown devices for this purpose. At P P there are cam-like supports for the arms n . These are secured to the shaft p , which is mounted at p' . Upon the shaft there is a worm-wheel p'' , with which engages a worm P^2 . The shaft P^3 of the latter extends down to the floor or to some other suitable place accessible to the operator. By the hand-wheel P^4 he can rotate the worm-wheel p'' and throw the cam-like rests or supports P up or down, so as to carry the arms n^2 into or out of their operative positions. When they are down, they are out of the paths of the trip-pins o and the buckets pass them without tilting.

The horizontal parts of the conveyer move along tracks Q , upon which fit the rollers C , and these support the load, so that it can move without friction. The roller-links B and the solid links B' are joined to the connecting-links by means of pintles b^6 and bushings or wearing-sleeves b^7 . Each pinte b^6 is oval or flattened and is of such shape as to be readily drop-forged, and therefore made hard, tough, and durable. Each side strap-bar b^5 is provided at each end with a corresponding oval or elongated aperture, and the bushings are each formed with a central similarly-shaped aperture. This construction is superior to those heretofore employed. The flattening of the pinte securely locks it against rotation in the side bars b^5 and also locks the

bushing or sleeve b^7 from rotation. The pinte has heretofore been locked against rotation in the outer side bars by means of webs 70 or pins, the main part of the pin being cylindrical in section, and the sleeve has been locked by forming a rabbet or shoulder at each end and fitting the rabbeted or shouldered part into a corresponding aperture in 75 the side bar; but by forging the pinte in the shape shown I obviate the necessity of these expensive features of the pinte and the labor incident to shaping and fastening the bushings or sleeves in the way described. The 80 sleeve or bushing b^7 being cylindrical on its exterior surface provides a large wearing-face at the place of articulation with an adjacent link. As represented in Figs. 5, 6, and 13 of the drawings, the pinte and the wearing sleeve or cylinder b^7 when assembled in working relations with the other parts of the links operate together as one part—that is to say, the wearing sleeve or cylinder partakes of the rotary movements of the pinte as 85 though it were integral therewith, the sleeve and pinte turning with the side bars of the link B^2 and in the end bearings of the next-adjacent link. The parts of the chain at the joints or articulations are secured together 90 by means of the heads b^8 at the ends of the pintles b^6 , these heads being formed by upsetting or riveting the ends of the pintles and arranged outside of the side bars b^5 . It will be understood that in case the rollers C are 100 omitted, as in lighter conveyers, a link like that at B' can be substituted for that at B , in which case the means for joining the links together can still be the same as those above described.

Buckets, flights, scrapers, and other material-transporting devices attached at the side of a chain produce violent strains and distorting actions which tend not only to rapidly wear but to break the articulating devices. When these material-transporting devices are connected together by links articulated to each other, as are those herein shown and described, these difficulties incident to conveyers are obviated, as those links of 115 the chain which may be considered as journal-links have relatively enlarged journal devices in the wearing-cylinders b^7 , which are fitted in correspondingly large and strong bearings in what may be called the "bearing-links," and there is therefore compensation for the lateral strains and distortions and the chains are properly held in straight lines notwithstanding the displacing tendency of the buckets or other carriers, and 120 this is enhanced by having these journal-cylinders b^7 locked tightly to the journal-links B^2 through the means of the flattened pinte ends b^6 . In conveyers of this sort, which are frequently used for transporting ashes, coal-dust, and other material having gritty particles, the articulating devices described are of importance, as the fine material is constantly being spilled in the path of the chain,

and when the ordinary pintles or connections are used the cutting and wearing at the surfaces of the pintles are serious; but with the present devices the trouble is largely obviated, because the flattened end parts of the pintles prevent wear in the apertures in the side bars of the links B^2 , and the large wearing-cylinders b^7 have so great a wearing-surface that the cutting and abrading become immaterial.

It will be seen that the chain is formed of elements each comprising a load-carrying or bucket link, a wheel or roller link with the centrally-disposed wheel, and two bar-links, one bar-link being articulated to each end of the wheel or roller link and the load-link being articulated to one of the said bar-links, and by this arrangement I am enabled to build up a chain such as is required for conveyor uses largely of steel parts, as the bar-links, pintles, and wearing-cylinders may be of steel, while the load-carrying links and the wheel or roller links may be formed of castings or forgings of a size sufficient to insure the requisite strength and of a length less than that of the bar-links.

What I claim is—

1. The combination, with the series of buckets, of the chain at each side of the buckets, each chain being formed of sets of links, each set comprising the solid bucket-link, B' , the roller-link, B , having side bars, b , and end sleeves, b' , integral with the side bars, b , and two connecting strap-links; the pivot or hinge 35 rod for the bucket journaled in two opposite bucket-links, B' , and the roller mounted centrally of the chain in the said roller-link, substantially as set forth.

2. The combination with a conveyor provided with swinging buckets, of the dumping mechanism having the initially-acting, swinging, trip-bar, adapted to engage with the buckets successively to start their tilting action, and a stationary tripper adapted to engage 45 with each bucket and continue said tilting action, substantially as set forth.

3. The combination with the endless conveyor having swinging buckets, of the dumping mechanism having an upwardly-movable trip-arm pivoted at a line below the buckets and arranged to engage with the bottom part 50 of the bucket and to move upward with said bottom, and a stationary trip adapted to engage with the upper part of the bucket, after it has been turned downward, substantially as set forth.

4. The combination with the conveyor having the swinging buckets, of the dumping mechanism having the upward-moving trip-arm, n^2 , with a projection, n^3 , adapted to engage with the bottom part of a bucket, the stationary trip, n^4 , and the lug or projection, o' , at the upper part of the bucket adapted to engage with the stationary trip, substantially as set forth.

5. The combination with the conveyor having a series of buckets secured thereto, of the

loading mechanism having a series of buckets, each with a permanently-closed bottom and an open side, means on each bucket for closing the open side of the preceding bucket when loaded, means for advancing the loading-buckets with substantially the same speed as the conveyer, and a chute for delivering material continuously to the loading-buckets; substantially as set forth.

6. In a conveyer, the herein - described chain, having links connected by means of the oval or flattened pintles, the bushings or wearing-sleeves provided with oval or flattened apertures for said pintles, and the sleeves, b' , fitted to the said bushings, b^7 , substantially as set forth.

7. In a conveyer, the herein - described chain, having the solid links, B' , with enlarged apertures at the ends, and the links, B^2 , each formed of a side strap-bar, b^5 , with the bushings, or wearing-sleeves, b^7 , at the ends, and the oval or flattened pintles passing through oval or flattened apertures in the side strap-bars and in the bushings, said bushings being seated in the end sleeves or apertures of the adjacent links, substantially as set forth.

8. In a conveyer the chain having draft-links, and one or more solid, forged wheel-supporting links, each wheel-supporting link being formed with side bars, b , and end sleeves or bearings, b' , integral with the side bars, b , and the side bars having perforations to receive a wheel-pintle, and an open space between them to receive a wheel; substantially as set forth.

9. The combination with an endless conveyor provided with carrying-buckets, of an endless loading-conveyer arranged above a substantially horizontal run of the said endless conveyer and provided with buckets adapted to transport material without dropping it for the desired distance and having closing bottoms and sides, and means for opening the said buckets of the loading-conveyer to discharge their loads directly into the buckets of the carrying-conveyer, substantially as set forth.

10. The combination of the endless conveyor having freely - swinging buckets, the endless loading-conveyer formed of chains and buckets rigidly secured thereto and having closing bottoms and sides, and arranged to receive material on their lower run, and means for opening the said rigid buckets as they begin to rise to deliver their contents to the swinging bucket, substantially as set forth.

11. The combination of the endless conveyor having freely - swinging buckets, the endless conveyer arranged above a substantially horizontal run of the aforesaid conveyer, and having buckets and chains secured rigidly together, each of the last said buckets having a closing bottom and an open side normally closed by the wall of the adjacent bucket, means for initially delivering material to the lower run of the loading-buckets;

ets, and means for opening the lower buckets as they begin to rise, substantially as set forth.

12. In a conveyer the combination with a series of material-transporting devices, of the chain connected therewith, said chain having the roller-carrying links and the intermediate links formed of flat straps or bars, and the pintles having flattened end pieces connecting the bars and the roller-links, substantially as set forth.

13. In a conveyer, the herein-described chain comprising a series of journal-links, a series of alternating bearing-links, and the connecting-pintles with flattened end parts fitting similarly-shaped apertures in the journal-links, and the enlarged wearing-cylinders—each wearing-cylinder being between the flattened ends of a pindle and rigid therewith against rotation thereon—fitted in the circular bearing-apertures in the said bearing-links, substantially as set forth.

14. In a conveyer, the herein-described chain comprising links with enlarged cylindrical bearings in their ends, and intermediate links adapted to be connected thereto having side bars with substantially oval-shaped apertures in their end portions, the enlarged wearing-cylinders fitted in the said enlarged cylindrical bearings, and a flattened pindle projecting from each end of each wearing-cylinder and fitted in said oval apertures, substantially as set forth.

15. In a conveyer, the herein-described chain comprising links with enlarged cylindrical bearings in their ends, and intermediate strap-bar links with non-cylindrical apertures in their end portions, the connecting-pintles uniting the said links having flattened end portions fitting the apertures in the said strap-bars, and the enlarged wearing-cylinders carried by the pintles and turning therewith arranged between the said strap-bars and fitting the enlarged cylindrical bearings in the adjacent links, substantially as set forth.

16. In a conveyer, the herein-described chain comprising links with enlarged cylindrical bearings in their ends, and intermediate links adapted to be connected thereto having side bars with substantially oval-shaped apertures in their end portions, the connecting-pintles uniting the said links and having end portions fitting the said substantially oval apertures and enlarged heads arranged outside of the end portions of the pintles and of the side bars of the links, and enlarged wearing-cylinders carried by the pintles and turning therewith and fitting in the said enlarged bearings in the links, substantially as set forth.

17. In a conveyer, the combination of a pair of parallel chains comprising links which are provided with supporting-wheels, tracks upon which the said wheels can travel, intermediate links normally unsupported by said tracks which unite the wheel-carrying links,

and the buckets or receptacles supported by the last said intermediate links, substantially as set forth.

18. In a conveyer, the herein-described chain comprising articulated links and supporting wheels or rollers arranged in the vertical longitudinal plane of the chain, and each mounted on an axis which is transverse relatively to the chain and is situated longitudinally between adjacent axes of articulation of the chain, substantially as set forth.

19. In a conveyer, the herein-described chain formed of articulated links, the supporting wheels or rollers arranged in the vertical longitudinal plane of the chain on axes other than the axes of articulation of the chain, and detachable wheel-supports independent of the link-articulating devices, substantially as set forth.

20. In a conveyer, the herein-described chain comprising load-carrying links and wheel or roller carrying links, with the wheels or rollers arranged in the longitudinal line of the chain, the said wheel-carrying links being intermediate the load-carrying links, substantially as set forth.

21. In a conveyer, the herein-described chain comprising load-carrying links, wheel-carrying links formed with wheel-chambers in the central longitudinal line of the chain, and strap-bar links connecting a wheel-carrying link and two adjacent load-carrying links, substantially as set forth.

22. In a conveyer, the herein-described chain comprising load-carrying links, the wheel-carrying links, and the intermediate connecting-links having side bars b^5 , the wheel-links each having a widened wheel-space with side bars in the lines of the side bars b^5 , and narrowed connecting parts b' between the side bars b^5 , and the supporting-wheels in the said widened wheel-spaces, substantially as set forth.

23. In a conveyer, the herein-described chain comprising load-carrying links, wheel-carrying links formed with widened wheel-chambers arranged centrally of the chain, wheels mounted in the said chambers, bar-links each having the side bars b^5 , enlarged wearing-cylinders fitting bearings in the load-links and in the wheel-links, and flattened pintles locked to the bar-links and rigid with the said wearing-cylinders against rotation relative thereto, substantially as set forth.

24. In a conveyer, the combination with material-transporting devices, of two parallel chains, each chain being composed of elements, and each element comprising a load-link, a wheel-link with a centrally-disposed wheel, and two bar-links, one bar-link being articulated to each end of the wheel-link, and the load-link being articulated to one of the said bar-links, substantially as set forth.

25. In a conveyer, the combination with swinging buckets and means for moving them, of a bucket-tilting device mounted upon a part of the structure that is stationary rela-

tive to the moving parts of the conveyer and which is movable with the bucket while tilting the same, substantially as set forth.

26. In a conveyer, the combination with 5 swinging buckets and means for moving them, of a tilting device arranged in the path of the buckets and movable toward the bucket while in the act of tilting it, substantially as set forth.

10 27. In a conveyer, the combination with a swinging bucket and a moving chain to which the bucket is connected, the tilting device having a bucket-engaging part which is movable toward the chain during the act of 15 tilting the bucket, substantially as set forth.

28. In a conveyer, the combination with a chain and the tilting buckets connected therewith, of a movable tilting device for the buckets mounted upon a part of the structure that 20 is stationary relative to the moving parts of the conveyer and is arranged to move in the direction of travel of a bucket while tilting it, substantially as set forth.

29. In a conveyer, the combination with a 25 chain and tilting buckets connected therewith, of a movable tilting device arranged to move with the buckets and to be disengaged therefrom after tilting them, and means for holding a bucket in the tilted position after 30 the tilting device is disengaged therefrom, substantially as set forth.

30. The combination with a conveyer provided with an endless supporting-chain and swinging buckets, of a tilting mechanism for 35 the buckets having a pivoted arm arranged adjacent to the path of the buckets, with its free end movable toward the supporting-chain and also in the direction in which the buckets are moving, and adapted to engage with 40 and to tilt the buckets, and means for adjusting the said arm whereby it may be moved into or out of the path of the buckets, substantially as set forth.

31. The combination with a conveyer provided with swinging buckets, of a tilting mechanism having a movable arm arranged when free to occupy a position to successively tilt the buckets, and arranged when engaged by a moving bucket to move into an unusual 50 position and at the same time tilt the bucket, and means for further tilting the bucket so as to release the said arm and permit it to automatically return to normal position, substantially as set forth.

55 32. The combination with an endless conveyer provided with carrying-receptacles, of an endless loading-conveyer arranged adjacent to the first said conveyer, and comprising a pair of endless parallel chains, receptacles or buckets for receiving, retaining and transporting material delivered to them connected with the said chains, each receptacle being arranged, when in working position, below the horizontal plane of the chains which 60 support it, and having independent sides, means for connecting the said independent

sides of each receptacle with different links whereby they move toward and from each other as the chains are deflected from straight lines, and means for deflecting the chains for 70 causing a discharge of the receptacles, substantially as set forth.

33. The combination with an endless conveyer having receptacles for transporting material, of a loading-conveyer for filling the receptacles of the first-named conveyer and comprising a pair of parallel chains, receptacles for receiving, retaining and transporting material delivered to them, each receptacle having opposite sides connected respectively 80 with different links of the chains whereby as the chains are deflected the said sides will be caused to move toward or from each other, means for holding the said independent sides of the receptacles in normal positions to close 85 the receptacles, and means for deflecting the chains to cause a separation of the sides of the receptacles to permit them to discharge their contents, substantially as set forth.

34. The combination with an endless conveyer provided with buckets or receptacles for transporting material, of a loading-conveyer comprising a pair of endless chains, buckets or receptacles carried by said chains and arranged to receive, retain and transport material delivered to them, each receptacle having independent opposite sides connected with independent links of the chains of the loading-conveyer, and connections between the receptacles and the chains arranged 100 at points intermediate the articulations of the links, and means for deflecting the chains of the loading-conveyer to cause a separation of the sides of the receptacles, and the discharge 105 of the contents thereof, substantially as set forth.

35. The combination of the swinging buckets, the conveyer-chains at the sides of the buckets, each chain comprising solid bucket-links having central bearings, longitudinally-extending arms and end bearings in the arms, and connecting-links uniting the said bucket-links, bucket-journals mounted in the bucket-links, and means for supporting the said chains, substantially as set forth.

36. In a conveyer, the combination with a series of material-transporting devices, of a chain for moving such devices comprising links having side bars, and enlarged removable wearing-cylinders connected with the side bars so as to turn therewith, other links having bearings arranged to fit the said wearing-cylinders and to articulate thereupon, and pintles uniting the said links, substantially as set forth.

In testimony whereof I affix my signature in presence of two witnesses.

ALFRED J. WEBSTER.
